UNITED STATES PATENT OFFICE

BEN J. CHROMY, OF HOPKINS, MINNESOTA, ASSIGNOR TO WIRED RADIO, INC., OF NEW YORK, N. Y., A CORPORATION OF DELAWARE

SOUND REPRODUCING DEVICE

Application filed September 17, 1928. Serial No. 306,540.

This invention relates to radio signaling systems generally and more specifically to sound reproducers.

An object of this invention is to provide a device for the reproduction of radio signals which will not be abnormally actuated by signals of greater than normal intensity.

Another object of this invention is to provide a loud speaker for radio signal reproduction which will respond only in normal intensity to signals of greater than normal intensity.

A further object of this invention is to provide a sound reproducing device for signal reproduction in which the sound intensity is automatically regulated.

Other and further objects of this invention will be apparent from the following specification and claims to one skilled in the sound reproducing art.

In this invention I provide a means for automatically controlling the intensity of sound reproduced by an electrical sound reproducing mechanism. This result is accomplished by providing a device within the loud speaker or sound reproducing mechanism for governing the density of the magnetic flux passing through or around the sound producing diaphragm or the diaphragm actuating armature. This flux density governing device may be adjusted to operate only when the electrical energy coming to the sound reproducing device from the signal amplifier is of such intensity as to produce distortion commonly called "blasting" in the reproducing device.

In the accompanying drawing Fig. 1 is a vertical sectional view of a sound reproducing device embodying this invention. Fig. 2 is a vertical cross sectional view of a magnetic diaphragm type of loud speaker unit embodying this invention. Fig. 3 illustrates a sound reproducing device in which this invention is incorporated is connected to an audion amplifier. Fig. 4 illustrates another schematic diagram of connections which may be used in this invention. Fig. 5 shows a fragmentary cross sectional view of a further modification of this invention.

Referring more specifically to Fig. 1 of the

drawing the reference character 1 designates a large loud speaker diaphragm commonly referred to as the cone type of diaphragm. The diaphragm actuating rod is designated by the character 2. The actuating rod is connected to the armature or movable coil 5 by the members 3 which engage the circumference of the coil. The armature moves in a magnetic field set up by the magnet 6. A small piece of magnetic material 7 may be disposed within the coil 5 to reduce the reluctance of the air gap. A highly resilient member 9 preferably of magnetic material is attached to the magnet 6 adjacent to the air gap within which the coil 5 is disposed. The screw 8 supports the member 9. A bar 9', also of magnetic material is attached to the member 9. A coil 10 is mounted upon the bar 9'. The coil 10 may be connected either in series or in parallel with the coil 5 to the output circuit of a signal amplifier. When signal energy of greater than normal intensity is fed to the sound reproducing mechanism the bar 9' is caused to move closer to the air gap of the magnet 6 by virtue of the magnetic flux set up in this bar through the action of the current in the coil 10 and the flux density in the air gap is decreased thereby reducing the intensity of the sound reproduced to normal. The bar 9' may be made of an alloy of cobalt and iron and may be magnetized into a permanent magnet.

A modification of this invention wherein a magnetic diaphragm is used for the production of sound waves is shown in Fig. 2. In this figure, 21 designates the diaphragm of magnetic material. The periphery of the diaphragm is mounted between the cap 22' and the housing 22. The bottom 22a of the sound reproducer housing 22 is attached to the side walls of the housing by screws 30. The housing may be made of phenol condensation products, hard rubber or similar insulating products. Other materials possessing very feeble magnetic properties may also be used.

A frame 23 which may be made of soft iron or other metallic materials possessing magnetic properties, is provided with pole pieces 23'. These pole pieces extend up-

100

wardly to close proximity of the diaphragm 21. The frame 23 is held within the casing 22 by screws 28 which extend through the bottom 22a. A coil 29, such as is employed in radio telephone head sets and loud speakers is mounted upon the frame 23. This coil is connected to the output of a radio signal amplifier or other signal amplifying system. The current flowing through this coil 29 magnetizes the frame 23 in accordance with the modulated signal energy. The diaphragm 21 is thus caused to vibrate in accordance with the modulated signal energy.

A movable bar 24b of material having a high magnetic permeability, such as soft iron or certain special alloys of nickel and iron is mounted upon the frame 23 adjacent to the pole pieces by means of a spring strip 24a. A coil 25 having a large number of turns of relatively fine wire, such as is used in winding telephone receiver coils of high impedance, is mounted upon the bar 24b. This small coil may be connected either in parallel or in series with the coil 29 to the output of a signal amplifier.

In Fig. 3 is shown a manner in which the device comprising this invention may be connected to a signal amplifier. In this figure, 15 indicates an amplifying thermionic vacuum tube or audion. The audion anode source of supply 14 is connected through the impedance 13 to the plate electrode. The volume or sound intensity governing coil and the diaphragm actuating coil of the sound reproducer are connected in parallel with each other to the output of the audion 15.

In Fig. 4 is shown another manner in which the device disclosed in this application may be connected to a signal amplifier. The coils 5 and 10 of the sound reproducer are connected in series to the output of the audion 15. The modified form of this invention shown in Fig. 2 may be connected to the output circuit of a signal amplifier 15 in any one of the ways shown in Fig. 3 and Fig. 4, that is the coil 25 may be connected either in series or in parallel with the coil 29 to the output circuit of the audion 15.

In Fig. 5 the armature coil 5a for actuating the acoustic diaphragm of a loudspeaker through the arms 3a is mounted between the pole pieces of a permanent magnet 6a. The magnetic flux deflecting bar 35 is supported against the magnet 6a by a resilient member 9a and screw 8a. Screws 32 and 31 are provided through the pole pieces of the magnet 6a. Coil springs 33 and 34 are provided to furnish adjustable tension against the bar 35. The force exerted by the springs 33 and 34 against the bar 35 may be varied by adjusting the screws 32 and 31 respectively. The intensity of the received signals at which the bar 35 will be caused to move closer to the pole pieces and deflect a greater percentage of the magnetic flux from the air gap

of the magnet 6a may thus be varied by adjusting either one or both of the screws 31 and 32.

Having thus described the preferred forms of my invention what I claim and desire to secure by Letters Patent is:—

1. In a sound reproducing device the combination of a diaphragm, electromagnetic means for actuating said diaphragm, and movable electromagnetic means adjacent said first named means for automatically governing the intensity of the sound reproduced. 75

2. In a sound reproducing device the combination with a signal amplifier of a diaphragm, electromagnetic means connected to the output of said signal amplifier for actuating the said diaphragm in accordance with signal energy fed into said means from the said amplifier, and electromagnetic means for governing the intensity of the reproduced sound waves, said last mentioned electromagnetic means being energized by energy from said amplifier. 80

3. In a sound reproducing device the combination of a diaphragm, electrodynamic means for actuating the said diaphragm in accordance with voice modulated electrical energy, a bar of magnetic material adjacent to said electrodynamic means for deflecting a certain part of the magnetic flux normally passing through said electrodynamic means, and a coil mounted upon the said bar, said coil being connected together with the said electrodynamic means to the output of a signal amplifier so that the magnitude of the current flowing through the said coil governs the displacement between the said bar and the electrodynamic means. 95

4. In a sound reproducing device the combination of a diaphragm, electrodynamic means for actuating the said diaphragm in accordance with voice modulated electrical energy, a resilient member, a bar of magnetic material supported adjacent to said electrodynamic means by the said resilient member for deflecting a certain part of the magnetic flux normally passing through the said electrodynamic means, and a coil mounted upon the said bar, said coil being connected together with the said electrodynamic means to the output circuit of a signal amplifier so that the magnitude of the current flowing through the said coil governs the displacement of the said bar from the said electrodynamic means. 110

5. The method of controlling the output of electromagnetic units comprising the steps of, impressing modulated electric currents upon a plurality of windings of an electromagnetic unit, vibrating a diaphragm through the interaction of a fluctuating magnetic field set up by said modulated electric current in one of said windings and a steady magnetic field and governing the magnitude of said steady magnetic field which 115

interacts with said fluctuating magnetic field through the action of another of said windings.

6. In sound reproducing devices the combination of a diaphragm, electromagnetic means for actuating said diaphragm and separate electromagnetic means operated in accordance with energy impressed upon said first mentioned electromagnetic means for 10 governing the intensity of the sound produced.

7. In a sound reproducing device the combination of a diaphragm, electromagnetic means for actuating said diaphragm in accordance with modulated electrical energy, a normally high reluctance magnetic shunt around said electromagnetic means, and electromagnetic means for controlling the reluctance of said normally high reductance 20 magnetic shunt around said first mentioned electromagnetic means.

In testimony whereof I affix my signature.
BEN J. CHRÖMY.
